Primary Examiner—Cathron Brooks*Assistant Examiner*—Barbara Fox(74) *Attorney, Agent, or Firm*—Nixon & Vanderhye, P.C.(57) **CLAIM**

The ornamental design for a “chain link,” as shown and described.

DESCRIPTION

FIG. 1 is a front elevational view of a chain link showing our new design;

FIG. 2 is a side elevational view of the design taken from the left of FIG. 1;

FIG. 3 is a side elevational view of the design, taken from the right of FIG. 1;

FIG. 4 is a rear elevational view of the design;

FIG. 5 is a bottom plan view of the design;

FIG. 6 is a top plan view of the design;

FIG. 7 is a perspective view of the design; and,

FIG. 8 is perspective view of the design taken from a different angle than FIG. 7.
